UNITED STATES PATENT OFFICE.

H. B. NASH, OF SANDY HILL, NEW YORK, ASSIGNOR TO A. B. KING, OF TROY, NEW YORK.

MITER-BOX.

Specification of Letters Patent No. 30,027, dated September 11, 1860.

To all whom it may concern:

Be it known that I, H. B. NASH, of Sandy Hill, in the county of Washington and State of New York, have invented a new and Improved Miter-Box; and I do hereby declare that the following is a full, clear, and exact description of the same, reference being had to the accompanying drawing, forming a part of this description, in which—

10 Figure 1, represents a transverse vertical section of my invention the line $x x$ Fig. 2, indicating the plane of section. Fig. 2, is a plan or top view of the same. Fig. 3, is a front elevation of one of the gates.

15 Similar letters of reference in the three figures indicate corresponding parts.

To enable those skilled in the art to make and use my invention, I will proceed to describe its construction, and operation with

20 reference to the drawing.

The platform A which serves to support the stuff to be cut rests on the standards B which are firmly secured to the bed plate C. Fastened to the bed plate C, by means 25 of a pivot a , is the angular arm D and the horizontal portion f^* of this arm sweeps over the half-circular slotted guide plate E, which is firmly bolted down to the platform C. Screws and nuts b serve to set the arm 30 D, to any point in the plate E, so that it can be adjusted to the desired angle. Another arm D' , similar to the arm D, and bent at right angles in the same manner as the latter, is made to slide on its horizontal 35 portion f'^* , being guided by a section c , fitting in slots d , d' , in the horizontal parts of both arms, and by grooves in the horizontal portion f^* , of the arm D, forming guides for corresponding ways on the under side 40 of the horizontal portion f'^* of the arm D' . By these means the upright portions of the arms D, D' , can be brought farther apart or closer together, as the nature of the stuff to be sawed may require, and at the same 45 time both arms turn together on the half circular guide plate E.

The ends of the guide plate E, are provided, with adjustable stops e' , which arrest the arms D, D' , at angles of 45° on 50 either side, and a mark in the center of the

guide-plate assists in adjusting the arms D, D' , to an angle of 90° . The upright portion of each of the arms D, D' , is made of two parts f , and g , which are screwed together by screw pivots n , thus allowing the 55 upper parts g , to turn freely and to be set to any desired angle. In order to arrest the arms g , when they are in a vertical position, shoulders i , are provided which by striking against stops j , on the lower parts f , prevent 60 the arms g , being turned any farther than necessary to bring them in a vertical position and other shoulders i' , on the opposite side of the arms g , by striking against stops j' , on the lower parts f , arrest the 65 arms, at an inclination of 45 degrees, it being most common to cut the stuff at angles of 90° or of 45° . But it will be easily understood how the arms can be adjusted by means of screws h at any desired inclination 70 between 45° and 90° . Each of these arms is furnished with two gates k which form the guides for the saw. The upper portion of these gates is enlarged so as to admit the back of the saw, and the lower portion of 75 these gates form either a continuous bearing for the saw blade as shown at l or steel pins C, are inserted into the inner edges of said gates to form the guides for the saw blade. I prefer the latter arrangement as 80 it creates less friction than a continuous bearing l .

The gates are made out of two halves which can be moved farther apart or brought closer together to suit different 85 thicknesses of blades and the gates are guided between the arms g , and adjustable plates m , which are set, to the desired distance apart by means of set screws. When thus adjusted the gates are allowed to move 90 up and down freely, the back of the saw serving to raise or depress the same, while the blade is always guided perfectly between the bearings l , or between the guide pins l' .

By these means any thickness of stuff may be cut to any angle between 90° and 45° in either direction, and as the teeth of the saw do not come in contact with the bearings l , or with the steel pins l' , there is no danger 100

of spoiling the cutting edge of the saw, and the gates will always preserve the width to which they have been adjusted.

What I claim as new and desire to secure 5 by Letters Patent is:

The arrangement of the sliding oscillating adjustable arms g , g , and parts f , f , with

the sliding pivoted arms D , D' , and adjustable guide gates k , k , as and for the purpose herein shown and described.

H. B. NASH.
